UNITED STATES PATENT OFFICE.

MARTIN D. MIESNER, OF OAKLAND, CALIFORNIA.

DAVENPORT.

Application filed July 31, 1924. Serial No. 729,265.

This invention relates to improvements in davenport beds of the type where the bed frame and mattress are folded within the seat of the davenport. The principal object of the present invention is to provide an improved folding bed frame for use in connection with the davenport, the said frame folding into small space in such a manner as to allow plenty of room for the mattress and bed clothes.

Another object of the invention is to construct the davenport in two sections, the upper part including the side arms, seat and back rest being removable from the lower part, whereby the davenport may be more easily handled and may be taken through doors and stairways through which the ordinary solidly constructed davenport cannot be moved.

With these and other objects in view, my invention consists in certain novel features of construction, combinations and arrangement of parts, herein illustrated and more particularly pointed out in the appended claims.

Reference being had to the accompanying drawings forming a part of this specification:

Figure 1 is a view in plan of the davenport and bed in open position.

Figure 2 is a similar view in side elevation.

Figure 3 is a view in section through the davenport showing the bed folded within the base thereof, and the upper portion raised from the base.

Figure 4 is an enlarged sectional view showing the connection between the base and the upper part of the davenport.

Figure 5 is a broken view showing the connection at the front of the davenport between the upper and lower parts thereof.

Figure 6 is a rear view of one of the hinge joints.

Figure 7 is a view in plan of the same.

Referring to corresponding parts in several views by the same numerals of reference, the davenport comprises a base 1 to which is removably attached the upper portion 2. As here shown, the latter is removable from the base 1 by removing the slotted

plate 3 which is secured to the upper portion 2 from the pin 3^a in the base 1. The upper edge of the base portion is provided with a groove 5, and the under side of the top portion with a corresponding tongue 4 which holds the two parts in longitudinal alignment. The base is provided with hooks 6 and the upper portion 2 has pins 7 for engagement with the hooks. The hooks 6 depend for a considerable distance below the pivot, which provides a reinforcement against lateral movement. This pin and hook connection is placed at the rear end of the davenport while the slotted plate and pin is placed at the front, the two holding devices effectively securing the parts together.

The folding bed arrangement comprises parallel side bars 10 between which is secured a wire fabric 11. The longitudinal side bars may be formed from angles and comprise sections 12, 13 and 14. Section 13 is pivotally attached to section 12 by means of the short trap 15 and section 14 is likewise attached to section 13 by means of a strap 16. One corner of each strap as shown at 17, and one corner of each angle section as shown at 18, is rounded to allow the parts to fit close together and yet turn on their pivots.

Angle section 12 is supported by the parallel links 19, the lower ends of which are pivotally attached to a bar 20 which is in turn rigidly attached to the end frame members of the base 1. The front 22 of the base 1, is hinged to the base as shown at 23 and secured to the inner surface of the front 22 are angle bars 24. Rollers 24^a are mounted on the upper end of the bars 24 to facilitate the opening of the bed. The member 13 slides upon the roller 24^a (see Fig. 3) which is a material aid in unfolding the bed. To the upper ends of these angle bars are pivotally connected links 25, the other ends of which are provided with a fastening device which is slidable in slots 26 formed in angle sections 14. The latter are supported by means of legs 27, the legs being held in a predetermined position by means of the links 28, each of which is pivotally attached at one end to the respective leg and at its other end

to the respective link 25. Pivots attached to each of the angle bars 24 is a link 30, the other end of which is pivotally attached to the respective angle bar 13 at the same point at which the respective forward link 19 is connected. At the head and foot of the bed I provide extension pieces 31 and 32 for the purpose of increasing the effective length of the bed and for holding the mattress and bed clothes in position. Each of these extensions consists of the angularly bent members 33 pivotally attached to the opposite side bars of the bed and which in turn are rigidly connected by the cross members 34. An arm 32' is rigidly attached to the leg 27, and a link 32^a is pivoted to said arm and to the extension 32 whereby said extension is automatically opened with the opening of the bed. A link 34' is pivoted 20 to the back of the lower part 1 and to the extension 31 whereby said extension is opened with the bed.

I provide a seat cushion and a back cushion, the former denoted by 40 is attached on each side to a bar 42 which is pivotally attached to a base as shown at 43. The bars 42 are extended beyond the pivot and to each extension is attached a spring 44. The seat cushion is positively locked in its raised position by means of the lock bar 45 which projects laterally from the bar 42. The lock bar is provided with a bent end 46 which is engaged by the rear link 19 when the bed is open, thus preventing the parts from rotating on the pivot 43.

The back cushion 41 is removably attached to the mechanism of the seat cushion by means of the pins 47 which engage the open slots 48 in the extension 49 on the side of bar 42. The back of the seat cushion slides on an abutment 50 which supports the cushion both in its raised and closed position.

When the davenport is folded and it is desired to convert it into a bed, the seat cushion is raised carrying with it the back cushion. Then the foot ends of the side angles 10 are raised upwardly and swung out of the base. This causes the legs 27 to fall in position and the links 19 to lock the cushions in their elevated position. The bars 42 and connected metal parts all lie close to the ends of the davenport and hence are concealed from view. The arms of the top part are connected to each other in any preferred manner, such as the bars 51 which have slotted plates 52 engaging pins 53 in the arms, and these arms are held in lateral position by the tongue and groove arrangement. When the davenport is to be moved the back cushion is lifted out, the top part moved around the pins 3^a and the hook 6 released. This allows the top to be lifted free of the base and so allows each piece to be moved independently.

As shown in Figures 6 and 7 rivet 60 has a large head which projects on the outside of angle 13. This head, under certain conditions, contacts with the link 25 and the latter is offset as shown at 62 so that when the link moves away from the end of the slot 26 it may pass the rivet head. This construction is used so that, when folding, the bed frame first folds at the joint between angles 12 and 13. As it folds at that point the upper end of the link 25 slides back in slot 26 which allows the frame to then fold at the joint between angles 13 and 14.

If the frame first broke at the joint of plate 16 the other parts would not move and it would become necessary to manipulate the several sections simultaneously whereas with the construction illustrated it can be folded by holding the foot section only.

The weight at the center of the bed is carried by the link 25 and it will be noted that the under side of this link contacts with the inside of angle 24 so that its upper edge cannot be depressed. The weight on this part of the bed tends to further open panel 25 which action is resisted by link 30 and the reaction of the latter is met by the latch 46, and the inclination of the legs 27.

Having thus described my invention, I claim as new:

1. In a davenport of the character described comprising a base section having a bed containing cavity, a front panel hinged at its lower edge to the base, a bed frame having parallel side rails, each side rail comprising end sections and an intermediate section hinged thereto, parallel links pivotally attached to the inner end section and to the base, a link connecting the upper edge of the panel with said inner end section, a link pivotally attached to the inside of said panel and having its upper end slidably and pivotally mounted in the outer end section, and a leg support for the said outer end section.

2. In a davenport of the character described comprising a base section having a bed containing cavity, a front panel hinged at its lower edge to the base, a bed frame having parallel side rails, each side rail comprising end sections and an intermediate section hinged thereto, parallel links pivotally attached to the inner end section and to the base, a link connecting the upper edge of the panel with said inner end section, a link attached to the inside of said panel so as to pivot on one side of the panel only, means pivotally and slidably attaching the upper end of said last mentioned link to the outer end section, and a stop on the side rail to prevent folding between the outer and intermediate sections until after the fold has started between the intermediate and inner end sections.

3. In a davenport of the character de-

scribed, a frame element, legs supporting the same adapted to be swung upwardly from a rearward horizontal position, a seat adapted to overlie the frame element and pivoted for swinging rearwardly into an upright position, and an extension arm associated with the seat made to be caught by one of the

upstanding legs when the seat is lifted for preventing the latter from swinging back into a horizontal position as long as the legs ¹⁰ are in an upward position.

In testimony whereof I affix my signature.

MARTIN D. MIESNER.
